UNITED STATES PATENT OFFICE.

CHARLES CLIFFORD SWARTWOOD, OF CENTRALIA, WASHINGTON.

EVAPORATIVE ICELESS REFRIGERATOR.

Application filed June 1, 1922. Serial No. 565,248.

To all whom it may concern:

Be it known that I, CHARLES C. SWARTWOOD, a citizen of the United States, residing at Centralia, in the county of Lewis and 5 State of Washington, have invented certain new and useful Improvements in Evaporative Iceless Refrigerators, of which the following is a specification, reference being had therein to the accompanying drawings.

10 This invention relates to iceless refrigerators of the character of that shown in my copending application, Serial Number 488,202, filed July 28, 1921, and in common with the structure shown in said application has for its object to provide an improved evaporative refrigerator which will be simple and economical in construction, will maintain the food receiving compartments thereof at a low temperature, without 15 the use of ice, will be suitably ventilated to prevent undue humidity in the food receiving compartments and to prevent the odors of one food from contaminating another food and to prevent the odors from foods 20 in the refrigerator finding their way into the room as in refrigerators which vent to the room in which the refrigerator is located and one which may be easily and quickly cleaned.

It is a further object of the invention to 30 provide a refrigerator of the character indicated adapted for direct connection to a service line of water supply and including means whereby the water level in the evaporative pan will be automatically maintained 35 at a given point and wherein the water may be automatically cut off when the evaporative pan is to be removed for cleaning or other purposes.

It is a further object of the invention to 40 provide an improved type of capillaceous elements adapted for use in conjunction with a refrigerator of this character and to provide an improved means of mounting such capillaceous elements so that they may be 45 readily removed, replaced or renewed.

Further objects and advantages of the invention will be set forth in the detailed description which follows.

In the accompanying drawings:

50 Fig. 1 is a longitudinal sectional view of a refrigerator constructed in accordance with the invention;

Fig. 2 is a transverse vertical sectional view therethrough;

55 Fig. 3 is a plan view thereof;

Fig. 4 is a horizontal sectional view upon line 4—4 of Fig. 1;

Fig. 5 is a view partly in side elevation and partly in section of a float controlled water supply valve hereinafter described; 60

Fig. 6 is a view partly in plan and partly in horizontal section of the valve illustrated in Fig. 5;

Fig. 7 is a perspective view of a capillaceous element hereinafter described; and 65

Fig. 8 is a perspective view of a modified form of capillaceous elements.

Like numerals designate corresponding parts throughout the several figures of the drawings. 70

In the particular embodiment of the invention illustrated in the accompanying drawings 5 designates a rectangular box-like casing having a fixed cover section 6 and a hinged cover section 7, the cover section 7 being hinged at 8 to the top of the casing 5. A knob or handle 9 provides means for swinging the hinged cover section 7 upwardly. A vertically disposed partition 10 extends from the front to the rear wall of the casing 5 leaving a vertical air passage 11 along one side of the casing 5 which may be provided with a damper 11^a. The partition 10 terminates short of the top of the casing so that air which passes upwardly through 80 the passage 11 and which enters said passage at the lower end thereof may pass laterally and in the direction of the arrows α across the upper part of the casing below the top sections 6 and 7 thereof and out of a flue 12, said flue being carried by the fixed section 6 of the top. In use the flue 12 is connected to a chimney much in the manner that a stove is connected to a chimney and the draft induced in said flue by its connection to the chimney creates a circulation of air upwardly through the passage 11 and across the top of the refrigerator and out of the flue 12 as will be readily understood. 90

This air in its passage is caused to travel 100 past capillaceous elements 13. These elements may be of any desired number and may vary widely in shape and in method of construction. In the present instance I have shown them as consisting of elongated 105 bands of cloth 14 mounted upon strips of metal 15, these strips of metal being received between lugs 16 formed upon the ends of an evaporative pan 17, said pan being adapted to receive a supply of water and the lower 110

2
portions of the capillaceous elements resting in said water. It is manifest that by virtue of this arrangement the upper portions of the capillaceous elements will be continually maintained in a wet condition and that by inducing a flow of air past these wetted surfaces the temperature of the water in the pan will be lowered with a consequent lowering of the temperature within the casing and within the food compartments of the refrigerator, hereinafter described.

The capillaceous element illustrated in Fig. 7 consists of a straight sheet of metal with a fabric covering thereon but I may, if desired, make these elements of zigzag formation, as illustrated in Fig. 8 and instead of using a solid core of metal such as is indicated at 15, I may make this of screen-like or other foraminous material, as indicated at 18 covering the same with a fabric covering 14^a. By using a screen-like core the air may pass through the fabric as well as over the same, if a fabric of sufficiently open mesh is used. Furthermore it is to be understood that the invention includes within its purview the use of the screen mesh 18 without the fabric covering 14^a, if desired. The evaporative pan 17 rests directly upon the top of an inner lining 19 constituting the walls of upper and lower food compartments 20 and 21. These food compartments may be separated from each other by a partition 22 which may be of any desired material but I preferably make it of open work formation so that ventilating air taken in through a ventilating opening 23 at the bottom may pass freely through the food compartments to a vent pipe 24 which passes through and is soldered to the bottom of the pan 17. The pipe 24 is designedly made of small diameter so that a very small circulation of air will be induced through the compartments 20 and 21. It is not desirable to maintain any considerable degree of circulation through this compartment because it is manifest that the introduction of air at outside temperature, in any large quantity, would tend to raise the temperature within the food compartments. Therefore, the degree of ventilation permitted by my arrangement is designedly kept small, being merely sufficient to prevent undue humidity in the food compartments and to cause any odors in said compartments to be carried off through the ventilating pipe 24 and discharged into the chimney through the pipe 12. It is to be noted that the pipe 24 is disposed immediately below the pipe 12 and that the flow of air through the pipe 12 tends to induce circulation from vent opening 23 to and through the pipe 24. In the present instance I have illustrated separate doors 25 and 26 for the compartments 20 and 21 but it, manifestly, makes no difference whether

one or two doors or more are used. A body of insulating material 27 is disposed about the lining 19 constituting the walls of the food compartments. This insulating material may be of saw dust, cork, mineral wool or any other suitable material. Certain methods of insulation are well recognized in the art, among them being the use of the materials mentioned or the omission of said materials leaving an air space, or the maintenance of a vacuum between the spaced wall and manifestly any of these well recognized methods of insulation may be employed without the exercise of more than 75 mechanical skill and judicious selection upon 80 the part of the builder.

It is desirable in an article of this nature to provide means for maintaining the water level at a given point in the pan 17 and this without any attention whatever upon the part of the user. To this end means are provided whereby the refrigerator may be sold as an article of manufacture with parts arranged to be directly connected to a surface water supply and through which 90 the water level may be maintained at a given point in the pan 17, indefinitely. To this end a pipe 28 is provided with a flange 29 adapted to be bound against the inner wall of the casing 5 by a nut 30 threaded 95 upon the outer portion of the pipe 28. This pipe is threaded at 31 for connection to an ordinary service supply pipe of water. The inner portion of the pipe 29 terminates in a head 30^a constituting a casing for a valve 100 plug 31^a. This valve plug carries a neck extension 32 which terminates in a downturned end 33 having a tapered valve seat 34 at its lower end adapted to be closed by a needle valve 35. This needle valve is formed upon 105 the stem 36 of a small float 37 and this float is prevented from dropping out of place by a cage 38 which is carried by the neck extension 32. The bore 39 of the pipe 29 alines with the port and bore 41 of the plug 31 and neck extension 32 when the parts are 110 in the position illustrated in Figs. 1, 5 and 6. With the parts in this position water may flow from the service line, and if the float 37 is in its lowered position will pass 115 out of the neck extension 32 and into the pan 17. When the level of the water in said pan reaches a predetermined height the float will be raised and the valve 35 will seat upon the seat 34 thus cutting off the passage of any more water into said pan until, by evaporation of water from said pan in the action of the refrigerator the water level becomes sufficiently lowered to permit the float to drop and unseat valve 35. 120

It will be desirable from time to time, to remove the pan 17 to thoroughly clean the same and to remove the capillaceous elements for a like purpose or to restore the fabric 14, 14^a of such elements or to substi- 125

tute new capillaceous elements for the old, if desired. When the pan is to be removed for these or any other purposes, the neck extension 32 may be swung upwardly and out of the path of the pan. The turning movement thus imparted to the plug 31 will bring the port 40 out of alinement with the bore of the pipe 39 and will thus automatically shut off the water during the time that the pan is removed.

The pan may be removed by opening the hinged section 7 of the top. It will be necessary to tilt the right hand end of the pan slightly upward during the removal of the same.

My improved evaporative refrigerator is very similar in appearance to refrigerators already in use and is adapted to fit in spaces ordinarily provided for the reception of such refrigerators. The structure is such that there is no tendency for the refrigerator to sweat. It is compact, economical of manufacture, provides a large food receiving capacity in proportion to the size of the refrigerator and is very easily kept clean.

While I have shown the invention embodied in an ordinary cabinet refrigerator it is to be understood that the principles may be embodied in built-in structures in homes, 30 hotels, apartments, boats, trains, refrigerator cars and the like. It is also susceptible of use as a cooling medium for stills, condensers or any other compartment to be chilled, the compartments illustrated not being limited 35 to use for the reception of food.

A very important feature of the present construction is that relating to ventilation of the food compartments 20 and 21. It is a well known fact that a dry cold preserves food 40 much more efficiently than a wet cold. A damp or humid atmosphere tends to cause food to mold and in the case of bread, cake and the like tends to cause such food to become soggy and worthless. Furthermore one 45 food product is much more likely to absorb odors from another food product in a damp atmosphere than in a dry atmosphere. All of these considerations render it highly desirable to produce a chilled compartment 50 which will be free from dampness and this is accomplished by inducing in the compartment a circulation of air in a limited quantity; just enough circulation to carry off any 55 humidity but not enough to impair the lowering of the temperature to any appreciable extent. Further it is to be observed that this circulation of air is carried out in such manner that the air enters at one side of the compartment and is discharged at the other 60 and that it enters at the bottom and is discharged from the top. Since the outside air is naturally warmer than the air within the chilled compartment it will be seen that the natural tendency of this air to rise is utilized 65 in aiding the circulation. It will further be

observed that the discharge of the air is at such a point that this air, carrying with it the odors from the food compartments, will be discharged into the flue 12 and into the chimney and it will never enter the room in which the refrigerator is located.

The pan itself may be of any suitable material, it may be of metal or it may be of vitreous material or it may be of metal covered with enamel. In short it is to be understood that the invention is not limited in any respect with relation to the kind of materials employed.

Particular attention is directed to the economical nature of the capillaceous elements employed. The metallic cores 14 and 14^a are good conductors of heat and in addition they are very economical to manufacture. It is, of course, apparent that the fabric coverings may be supplied at a very small cost.

While I prefer to employ a float controlled valve in conjunction with a service supply pipe it is to be understood that the invention is not limited in this respect because, if desired, I may employ the pan 17 without this water supply feature and if this pan be made of sufficient capacity it will hold enough water to last for a considerable length of time without replenishing the same. However, it is, of course, desirable to provide a structure which will not require any attention whatever, if possible and to that end the float valve and water supply connection are provided.

It is to be understood that the invention includes within its purview whatever changes fairly come within either the terms or the spirit of the appended claims.

Having described my invention what I claim is:

1. In combination a casing, a food compartment therein spaced from the casing of one side thereof to leave a vertically extending passageway which is open at the bottom to the entrance of atmospheric air, a flue leading from the top of the casing at the opposite side thereof, a removable evaporative pan above said food compartment and capillaceous elements in said pan extending in the direction of the flow of air from said passage to said flue.

2. A structure as recited in claim 1 in combination with means to admit air of ventilation to the lower part of the food compartment and a ventilating pipe carried by the evaporative pan and communicating with the upper part of the food compartment and disposed in alinement with said flue.

3. A structure as recited in claim 1 in combination with a source of water supply and a float controlled valve for the same for maintaining a constant level of water in the evaporative pan.

4. In an evaporative refrigerator an evaporative pan, capillaceous elements seated in said pan and a water supply pipe comprising a movable part carrying a float valve and a shut-off valve actuated by the movement of said movable part.
5. In an evaporative refrigerator an evaporative pan, capillaceous elements therein, a water supply pipe, a neck extension pivot-
10. ed to said water supply pipe, a cage carried by said neck extension, a float in said cage, a valve carried by said float adapted to control the flow of water through the neck extension and a shut-off plug constituting a
15. part of the pivotal connection between the neck extension and the water supply pipe.
6. In combination a casing, a fixed top section, and a hinged top section for said casing, a flue secured to and leading from the
20. fixed top section, food compartments in the casing, an evaporative pan above the food compartments removable through the hinged top section, and capillaceous elements in the evaporative pan.
25. 7. A structure as recited in claim 6 wherein in said food compartments are spaced from the wall of the casing to leave a vertical passageway open at the bottom along one side of said casing, atmospheric air entering said vertical passageway and passing along said capillaceous elements and entirely across the casing and out of said flue.
8. In combination a casing, food compartments therein spaced from the wall of the
35. casing at one side thereof to leave a vertical passageway which is open at the bottom for the entry of atmospheric air, an evaporative pan upon the top of said food compartments, a fixed top section and a hinged top section for said casing, a flue carried by the
40. fixed top casing, means for admitting ven-
- tilating air to the lower part of the food compartments, a ventilating pipe carried by the pan and disposed in alinement with said flue and communicating at its lower end 45 with the upper part of the food compartment and capillaceous elements disposed in said pan.
9. A structure as recited in claim 8 in combination with a water supply pipe and 50 means for maintaining a predetermined level of water in the pan from said water supply pipe.
10. In combination a capillaceous element comprising a metallic core in the form of a 55 flat plate like material and a covering of fabric, which covers both sides of said core.
11. In combination an evaporative pan and a plurality of capillaceous elements each comprising a flat core of metal and a covering of fabric extending around both sides thereof and means at the ends of said pan 60 for engaging said metallic cores to hold said capillaceous elements on edge in place in said pan.
12. In an evaporative refrigerator, a casing, a flue adapted to be connected to a chimney, capillaceous elements in the casing, means for supplying water to said capillaceous elements, means for admitting air to the 65 casing at that side of the casing remote from the flue, said capillaceous elements being disposed in the path of the air as it travels toward said flue, a food compartment and a ventilating means of restricted capacity for 70 said food compartment aligned with and discharging into said flue under the influence of the draft induced in said flue.

In testimony whereof I hereunto affix my signature.

CHARLES CLIFFORD SWARTWOOD.
